[57] CLAIM

The ornamental design for a golf accessory holder, as shown.

DESCRIPTION

FIG. 1 is a front elevational view of a golf accessory holder showing my new design;

FIG. 2 is a top plan view thereof;

FIG. 3 is a bottom plan view thereof;

FIG. 4 is a rear elevational view thereof;

FIG. 5 is a right side elevational view thereof;

FIG. 6 is a left side elevational view thereof;

FIG. 7 is a top, front, right perspective view thereof; and,

FIG. 8 is a top plan view thereof in open position with the strap portion, shown fragmentarily for convenience of illustration.

The broken line showing of golfing accessories and strap portion is for illustrative purposes only and forms no part of the claimed design.
